J.B. Root,
Rotary Steam Engine,
Patented Sep. 15, 1863.
N° 39,957,

UNITED STATES PATENT OFFICE.

JOHN B. ROOT, OF NEW YORK, N. Y.

IMPROVED STEAM-ENGINE.

Specification forming part of Letters Patent No. 39.957, dated September 15, 1863.

To all whom it may concern:

Be it known that I, JOHN B. ROOT, of the city, county, and State of New York, have invented certain new and useful improvements in engines for obtaining motive power from steam or other fluid, also partly applicable to pumps; and I do hereby declare that the following is a full, clear, and exact description of the same, reference being had to the accompanying drawings, forming part of this specification.

The principal feature of this invention consists in the combination of two pistons—one of which is hollow and fitted within a parallel-sided box, which may be termed the "cylinder" of the engine, in such manner as to be capable of a reciprocating rectilinear motion therein, and the other is fitted to the interior of the first one in such manner as to be capable of a reciprocating rectilinear motion therein in a direction at right angles to the first-mentioned reciprocating rectilinear motion, and the inner one is connected directly with a crank.

In an engine to be used as a motor, the steam or other fluid from which the power is obtained is admitted by a suitable valve or valves to the outer box or cylinder, and to the interior of the outer piston in such manner as to act first on one and afterward on the opposite side of each piston and to commence operating on either side of one piston when the other piston is at half-stroke, so that it acts upon both pistons at once to produce a rotary motion of the crank, which is thereby made to transmit the power without ever being at a dead-point.

In a pump the motion of the crank produced by a suitable application of power to its shaft sets the two pistons in motion at right angles to each other, and the water or other fluid is thereby drawn into and expelled from the cylinder and outer piston through a suitable valve or series of valves.

The invention also consists in a mode of preventing the leakage of steam between the surfaces of the sides of the piston and the cylinder-heads of the engine, and for compensating for the wear of those parts of the engine.

It also consists in the employment, for the induction and excretion of steam or other fluid to and from an engine or pump having such a

system of pistons as above mentioned, of a valve composed of a flat disk or ring with an annular cavity in its face, and fitted directly to an eccentric, which is provided upon the crank-shaft, and is arranged within the steam-chest or induction-chamber. The seat against which this valve works contains four ports, two of which communicate with opposite ends of the cylinder, and two with the interior of the larger or outer piston on opposite sides of the smaller or inner one, and the valve, deriving from the eccentric an eccentric circular motion, is made to uncover each port in turn for induction and bring each in turn into communication with the annular cavity in its face, which is always in communication with an annular excretion-channel formed in the seat.

It further consists in a mode of providing for the shifting of the aforesaid eccentric on the crank-shaft for the purpose of changing the relation of the valve to the pistons in such manner as to produce the revolution of the engine in one direction or the other, or effect its reversal.

The invention relates, finally, to a mode of lubricating the crank-wrist and its bearing. These being within the inner piston cannot be reached by any ordinary means of lubrication, and, owing to their being always highly heated by the steam when the engine is in operation, it is especially desirable that they should be well lubricated.

Figure 1 in the accompanying drawings is an elevation taken perpendicular to the main shaft of a steam-engine, illustrating the several features of the invention, representing the valve-chest cover removed to expose the valve to view. Fig. 2 is a vertical section right through the cylinder and pistons of the engine in a plane parallel with Fig. 1. Fig. 3 is a vertical section directly through and parallel with the axis of the shaft of the engine. Fig. 4 is an inside face view of one of the cylinder-heads. Fig. 5 is a horizontal section of the cylinder-head and packing-plate in the plane indicated by the line xx in Fig. 4. Fig. 6 is a diagram illustrative of the construction and arrangement of the valve-ports. Fig. 7 is a face view of the valve.

Similar letters of reference indicate corresponding parts in the several figures.

P is the bed-plate of the engine.

A is the "cylinder," so called, not on account

of its form, but because it corresponds in its functions with the cylinders of other engines. The form of the interior of this cylinder is parallelopipedal. Its body is made double, to form a jacket, *a*, and one or both of its heads, *B* and *C*, are movable. Both are represented movable in Fig. 3.

D and *E*, Figs. 2 and 3, are the pistons, both fitted to work steam-tight between the cylinder-heads. These pistons may be packed to one of the said heads with springing or adjustable packing of any suitable kind to compensate for wear of the surfaces of the pistons and cylinder-heads; but I prefer to employ an adjustable plate, which will be hereinafter more fully described, instead of any other packing. The outer piston, *D*, consists simply of an open frame, the length of which is exceeded by the length of the cylinder by at least twice the length of the crank of the engine, and the said piston is fitted steam-tight between the upper and lower sides of the cylinder and packed thereto by spring-packing *b b*, as shown in Fig. 2. The inner piston, *E*, is made of a depth from top to bottom which is as much less than the vertical depth of the interior of the outer piston, *D*, as the length of the exterior of the latter is less than the length of the cylinder, and the said piston *E* is fitted to work steam-tight between the flat upright sides of the piston *D* and packed thereto with elastic or other packing *c d d*. The steam-chest *F* is formed within or secured to the cylinder-head *B*, and of its four ports, *e e' f f'*, two, *e e'*, communicate with opposite ends of the cylinder outside of the piston *D*, and two with the interior of the piston *D*, one above and the other below the piston *E*. The main shaft or crank-shaft *G* of the engine works in bearings in the centers of the two cylinder-heads, and another bearing is provided for it in a standard, *H*, outside of the cylinder. The wrist plates or arms *G' G²* of the crank are received in cavities formed in the piston *E*, and the wrist *g* is received in a bearing provided for its reception in the center of the said piston. Steam admitted to and exhausted from the cylinder *A* by the ports *e* and *e'* alternately produces a reciprocating movement of the piston *D* within the cylinder, and steam admitted to and exhausted from the interior of the piston *D* by the ports *f* and *f'* alternately produces a reciprocating motion of the piston *E* within the piston *D* at right angles to the movement of the latter within the cylinder, while the piston *D* is at the same time moving with *E*, and the force of the steam acting on both pistons is made instrumental in producing a rotary movement of the crank and its shaft. The admission or induction of steam to the ports *e e'* should commence when the piston *E* is at half-stroke, and the induction to *f f'* commence when the piston *D* is at half-stroke.

The order in which the induction to the four ports should commence will vary according to the direction in which the shaft is intended to

rotate. For the direction indicated by the arrows 10 in Figs. 1 and 2 the order will be *e f e' f'*, and for the opposite direction it will be *e f' e' f*.

In order to reduce as much as possible the friction between the piston *D* and the cylinder, recesses 17 17 are formed all across the upper and lower faces of the said piston for the greater portion of their length, as shown in Fig. 2, for the admission of steam between them and the upper or lower side of the cylinder, and corresponding recesses 18 18 are formed in the sides of the said piston, as shown in Fig. 3, and by dotted lines in Fig. 2, to allow steam to pass from the interior of the said piston to the recesses 17 17. This leaves only a sufficient portion of the ends of the piston to insure tight working, fitting between the heads of the cylinder, and the steam in the recesses 17 17 counteracts the upward and downward pressure of the steam against the upper and lower sides of the said piston, and so prevents the excessive friction which would otherwise be produced between the said piston and the cylinder. To reduce in like manner the friction between the sides of the piston *E* and the interior of the piston *D*, recesses 19 19 are made in the outer side faces of *E*, and small holes 20 20 provided in the upright ends of *D*, as shown in Fig. 2, to admit steam from the cylinder *A* into the said recesses. The adjustable side plate, which is employed for keeping the pistons steam-tight within the cylinder, is shown at the right side of Fig. 3, fitted to the cylinder-head *C*, and as also shown in Fig. 5. (Indicated by the letter *Q*.) This is simply a rigid flat plate, of cast-iron or other metal, of a form corresponding with the longitudinal vertical section of the cylinder, which is shown in Fig. 2, and having a central opening for the crank-shaft bearing, and it is fitted into a recess, 21, of corresponding form, in the interior of the head *C*. No packing is employed in the opposite head, which is simply faced flat for the pistons to work in contact with. In Fig. 3 the plate *Q* is represented as adjusted to the sides of the pistons by means of set-screws *v v*, screwing through the head *C* from the exterior thereof, and is thereby not only held against the contiguous sides of the pistons in such manner as to form a steam-tight working-joint, but made to hold the opposite sides of the pistons against the head *B* in such manner as to keep them steam-tight, and the wear of the pistons on both sides of the engine is compensated for by screwing up the screws *v v*. In Fig. 5 the said plate *Q* is represented as adjusted to the pistons by means of wedges *y y*, formed upon the outer face of a frame, *R*, which is arranged between the said plate and the cylinder-head *C* in the inner part of the recess 21. This frame *R* is also shown in Fig. 4. The wedges *y y* are arranged in two series—one series on the upper and the other one on the lower side of the said frame—and work in contact with corresponding inclined surfaces

zz, provided in the recess 21, as shown in Fig. 5. The adjustment of the frame R is effected and secured by means of a set-screw at each end of the cylinder, screwing through tapped holes in the said cylinder-head and bearing against the ends of the said frame, and by this adjustment all the wedges are brought simultaneously into operation to press the plate Q against the pistons, and as they are all of similar inclination all act equally upon the plate, and so press all parts equally against the pistons.

The advantage of the employment of the wedges attached to a frame, R, over the use of the set-screws vv is that their uniform action on all parts of the plate is obtained by a single screw at each end of the plate, while the screws vv require to be adjusted separately, and it is difficult, if not impossible, to make all press exactly alike against the plate Q.

I, Figs. 1, 3, and 7, is the valve for the induction and eduction of steam, consisting of a circular disk or ring, having an annular cavity, i, in its face, which is otherwise flat and fitted to the flat seat j, provided in the steam-chest, the said seat being perpendicular to the axis of the main shaft G, and parallel with the plane of motion of the piston E. The back of this valve is fitted to work against the flat inner surface of the steam-chest cover F', and provided with suitable packing, j, so that the steam only occupies the portion of the chest around the periphery of the said valve. The central opening, k, of the valve is fitted loosely to the eccentric J, which is carried by the main shaft, and the valve is thereby caused to have an eccentric circular motion, by which it is caused to open the several ports successively to the steam-chest and to bring them successively into communication with the annular exhaust-channel l, which is provided in the valve-seat and arranged concentric with the shaft G, the latter communication being made through the annular cavity i in the valve-seat. The form of the outer orifices of the ports e e' f' f'' is illustrated in Fig. 1, and in the diagram, Fig. 6. The mode of setting out these orifices is as follows: First, strike around the center of the seat coinciding with the axis of the main shaft a concentric circle, 12, and draw through the center of the said circle a horizontal right line, 15 15, and a vertical right line, 16 16; then with a radius equal to half the diameter of the outer circle of the valve, from points to be presently mentioned in the aforesaid circle, strike the lines of the outer edges of the ports, and from the same points, with a radius equal to half the diameter of the outer circle of the central cavity, strike the lines of the inner edges of the ports. If the valve is allowed to have no lead, the lines are to be struck from the points of intersection of the lines 15 and 16 and the circle 12, but if a lead is required they are struck from points more or less distant from opposite sides of the aforesaid points of intersection. In the exam-

ple represented the valve has a lead and the ports are struck from the points e* e'* f* f'', as may be found by applying the compasses to those points. The eccentric is set in advance of the crank G in the direction of their revolution to the extent of ninety degrees of a circle, but to these ninety degrees must be added the required number of degrees of lead, when lead is to be given to the valve. The valve thus constructed and operated will commence opening one of the four ports to the steam in the steam-chest at every quarter-revolution, at the same time opening the opposite port to the exhaust-channel l, the order of their opening being, as before described, according to the direction of the revolution, and the ports each remaining open during half a revolution of the crank-shaft. As each port is wide open, and its respective piston at half-stroke, and the crank at or nearly at a right angle with the direction of the reciprocating movement of that piston at the time when the next port is commencing to open and the other piston is at the change of its stroke, and the crank in line or parallel with the direction of its movement, when one piston is exerting the least effect on the crank, the other is exerting the greatest, and hence there are no dead points in the operation of the engine. The exhaust-steam passes from the annular exhaust-channel l through any suitable number of passages m m, dotted in Figs. 1 and 3, into the jacket a, and thence by an opening, n, into the hollow bed-plate P, which may also serve as a heater for heating the feed-water on its way to the boiler. The steam-pipe from the boiler connects with the cylinder at u, and communicates with the chest F by means of a passage, w.

p is the toothed arc, q the spur-gear, and r the pinion by which the shifting of the eccentric to set it for producing the rotation of the crank-shaft in one direction or the other is produced. The toothed arc p is arranged and firmly secured within a cavity, s s', provided in the eccentric. Its teeth are on the inner curve and their pitch-line concentric with the shaft G. The spur-gear q, gearing with the said arc, is arranged to turn freely upon the pin q', which is carried by a short arm, L, which is secured on the shaft G in such manner as to rotate with it, the axis of the said pin being parallel with the axis of the shaft. The portion of the shaft which enters and protrudes through the exterior of the eccentric J is bored out centrally for the reception of the pinion r, which gears with the gear q, and of the spindle r', to which it is secured, and an opening is cut in one side of the said portion of the shaft, to meet the said central bore and admit the teeth of the gear q' to gear with the pinion r. The spindle r' is furnished with a fast collar, r'', which covers the end of the shaft G, and a cap, F'', screwed or otherwise secured to the exterior of the steam-chest cover F', fits against the said collar r'', and secures the spindle r' and pinion r in place,

the said cap having a central opening through which a portion of the spindle protrudes for the reception of the wheel M, to enable the pinion and spindle to be turned by hand or other means, for the purpose of turning the eccentric on the shaft. To prevent any leakage of steam around the spindle r' the wheel M is arranged against the cap F, and fitted with a packing-ring, t, which is pressed against the said cap by springs. The arm L is so arranged that a portion of it is received within the cavity $s s'$, and it drives the eccentric by coming into contact with one side or other of the said cavity, according to the direction in which the engine is running, and no movement of the arc p , gear q , and pinion r , relatively to each other, takes place while the engine continues running in one direction. The said arm L is made of such width, and the cavity $s s'$ of such width or diameter, that the eccentric will be permitted by the said arm to turn upon and independently of the shaft to the extent of half a revolution when no lead is given to the eccentric, or to the extent of half a revolution minus double the amount of the lead of the eccentric when lead is given. The eccentric is turned on the shaft to set it, when the engine is at rest, by turning the wheel M, which, by turning the pinion r , causes the latter to turn the gear q , and this gear operates on the toothed arc p to turn the eccentric. When the engine is in operation, the spindle r' rotates with the main shaft G, and whenever it is desired to reverse the motion, all that requires to be done is to stop the wheel M, either by taking hold of it by hand or by applying a friction-brake, or by other means, and thereby stop the revolution of the pinion r until the reversal is effected. The stoppage of the pinion r' while the gear q is carried around it by the continued revolution of the arm L, causes the said gear to turn on the pin q' in such a direction that it will, by its action upon the arc p , cause the eccentric to rotate faster than the shaft in the same direction, until the opposite side of the cavity $s s'$ to that which has previously been in contact with the arm L comes in contact with the said arm, and the eccentric and valve are thereby brought to proper position relatively to the crank-wrist g , for effecting the induction and ejection to and from the several ports, in the proper order of succession to change the direction of the revolution of the crank-wrist. This action of the pinion may be perhaps rendered more intelligible by describing it with reference to Fig. 1, where the shaft and valve are rotating in the direction of the arrows 10, the arm L driving the eccentric by pressing against the side s of the cavity $s s'$, but by stopping the pinion r the gear q is caused to rotate upon the pin q' in a direction to turn the eccentric forward upon the shaft in the same direction as the shaft is rotating, and bring the side s' into contact with the arm L. When the reversal of the action of the pistons upon the crank-wrist has taken place, the

arm L drives the eccentric in the same direction as the crank-shaft—that is to say, in the opposite direction to that indicated by the arrows 10 10—by pressing against the side s' of the cavity s .

T is an air-tight oil-chamber, formed in the upper part of the cylinder-head C, with a passage, 23, from the bottom leading directly to the crank-shaft bearing 22—that is, contained within the said head—and with an opening in the top for supplying it with oil. The upper opening is fitted with a screw-stopper, 30, to make it steam-tight, and the passage 23 is fitted with a cock, 24, to enable it to be closed during the time that the chamber T is being filled. There is also a passage, 25, leading from the steam-passage u' into the upper part of the said chamber, and the said passage is fitted with a valve, 26, which can be opened and closed by a screw or other device operated by a handle, 27, outside of the cylinder-head. The passage 25 communicates with a groove or channel in the interior of the bearing 22, and this channel communicates with a passage, 28, which is drilled in the center of the crank-wrist g and through the wrist-plate or arm G', and from which there branch off the radial passages 29 29, drilled from the periphery of the wrist, to communicate with the bearing 31. To fill the chamber T with oil, the cock 24 is closed to prevent the steam from flowing through the passage 23 from the interior of the cylinder A, and the valve 26 is closed to prevent the steam in the passage u' from blowing through the passage 25, and the stopper 30 is then removed and the oil poured into the chamber. When the chamber has been charged with oil, the stopper is replaced, and when it is desired to oil the crank-wrist bearing the cock 24 and the valve 26 are opened, and steam, entering the upper part of the chamber and pressing upon the upper surface of the oil, forces a portion of it through the passage 23, the channel in the bearing 22, the passage 28 in the wrist-plate or arm and wrist, and the passages 29 in the wrist. This oiling operation may be performed periodically, or may be made continuous by leaving the valve 26 and cock 24 a little way open to allow the oil to flow to the bearing 31.

To prevent the cutting of the crank-wrist and its bearing, I propose to fit the wrist tightly with a sleeve, 32, of hardened steel, and to make the lining of the bearing of an alloy composed of copper, with very small proportion of tin.

The leakage of steam through the crank-shaft bearing 22 is prevented by a collar, U, which is fitted tightly to and secured upon the shaft close to the cylinder-head C, and fitted with a packing-ring 33, which is held up to the cylinder-head by springs.

A pump may be constructed in precisely the same manner as the steam-engine, and operated by power applied directly to the shaft outside of the cylinder to produce its rotary motion, the suction-pipe being connected at

u and the discharge-pipe with the jacket *a*, or directly with the channel *l* in the valve-seat, the jacket being unnecessary. The rotary motion of the shaft produces the same reciprocating movements of the two pistons and the eccentric circular motion of the valve as is produced by the action of the steam upon the pistons, and by these movements of the pistons the water is drawn into the cylinder *A*, through the ports *e* and *e'*, and into the piston *D* through the ports *f* and *f'*, and forced out through the same ports into the channel *l*; but it is obvious that in a pump, as in an engine, and more especially in a pump, the same system of pistons may be made to work in the same way with a different valve or system of valves.

What I claim as my invention, and desire to secure by Letters Patent, is—

1. The two pistons *D* and *E*, combined with each other and the cylinder *A*, and crank-shaft *G*, to operate substantially as herein specified.

2. The packing-plate *Q*, applied in combination with the cylinder-head *C*, and the two pistons *D* *E*, substantially as and for the purpose herein set forth.

3. The wedge-frame *R* and its double series of wedges *y* *y*, applied in combination with the cylinder-head *C* and packing-plate *Q*, to operate substantially as and for the purpose herein described.

4. The eccentrically-moving disk or ring valve *I*, constructed with an annular cavity *i*, and operating substantially as herein described.

5. Combining the valve-operating eccentric *J* with the crank shaft *G*, by means of the arm *L* and the toothed gearing *p*, *q*, *r*, or its equivalent, substantially as and for the purpose herein set forth.

6. Providing for the lubrication of the crank-wrist bearing by means of channels or passages made in the wrist and wrist plate or arm of the crank, and communicating with the journal box or bearing provided for the shaft in one of the cylinder-heads, substantially as herein described.

7. An engine composed of a cylinder, *A*, two pistons, *D* *E*, working one within and at right angles to the other in the said cylinder, a shaft, *G*, furnished with a crank connecting directly with the inner piston, *E*, and a valve, *I*, and system of ports *e* *e'* *f* *f'*, for effecting the induction and ejection of the steam or other liquid to and from the cylinder and the interior of the outer piston, the whole operating substantially as herein described.
